CHUTE SUPPORTING MEANS

Gail D. Beaver, Norristown, Pa.

Application March 7, 1931, Serial No. 520,941

6 Claims. (Cl. 193—34)

My invention relates to the supporting of a chute for linen or the like, particularly an aluminum chute installed within a multi-story building.

5 A purpose of my invention is to provide a chute of the character indicated installed within a multi-story building with supporting connections with the individual floors of the building that will avoid the extension of rivets into the interior of 10 the chute, that will be adapted to easily accommodate variant conditions at different floors and adapted to easy and inexpensive manufacture and installation.

A further purpose is to support a chute of the 15 character indicated by circumferentially spaced flaps, preferably of the same metal as that forming the chute, suitably welded to the body of the chute, and individually extended upwardly over a vertical flange and thence downwardly to a 20 suitable fastening, the top of the flange supporting the flap from downward movement and the close bend of nearly 180° about the top edge of the flange greatly reducing the pull on the flap at its point of fastening.

25 A further purpose is to weld flaps to a section of a chute of the character indicated at circumferential intervals and to support each flap against downward movement by an upwardly directed flange of a preferably straight horizontal angle individual to the flap, bolting the extended 30 end of the flap down to the lower and horizontal side of the angle after it has passed over, upwardly to and downwardly from, the upwardly directed side of the angle.

35 Further purposes will appear in the specification and in the claims.

I have elected to show one only of the many different forms of my invention, selecting a form that is practical and efficient in operation and 40 which well illustrates the principles involved.

Figure 1 is a fragmentary side elevation, partly in section, illustrating structure embodying one form of my invention.

Figure 2 is a horizontal section of Figure 1 taken upon the line 2—2 thereof.

45 Figure 3 is a reduced scale view corresponding to Figure 2 but showing a variation.

Like numerals refer to like parts in both figures.

50 Describing in illustration and not in limitation and referring to the drawing:—

My invention is believed to find its best application with linen chutes such as are used with multi-story buildings, the chute often running from the top floor to the basement with inlets at

the individual floors and an outlet in the basement, my invention being directed to the supports of the main chute section at the individual floors. For the chutes I prefer to use aluminum, although the chutes may be made of any other metal, as for example enamel-coated steel, suitable for the purpose.

The chute proper 6 is made of thin sheet material, preferably aluminum or other metal unable to stain linen or the like passing down the chute, for which reason the whole interior surface of the chute should be free from any exposed metal surface subject to oxidation under the service conditions within the chute, which, I find in practice, makes it desirable to eliminate rivets and indeed the exposure of any metal except aluminum on the interior of the chute. The projection of rivet heads into the chute is also undesirable, as it may cause the charge of the chute to catch or be torn.

70 The main chute section 6 will usually be vertical for a long distance, passing up through floor openings 7 at any number of floors 8, the chute being made up of successive sections 9 and 9' having joints 10 located without regard to the floor levels, and the chute having a supporting connection of my invention with each floor.

75 I provide the chute at circumferentially spaced intervals at each floor with metal flaps 11, desirably of sheet material of the same metal that makes up the body of the chute. For an aluminum chute, I preferably use aluminum or an aluminum alloy to permit easy welding.

80 The flaps 11 are hangers, fastening at their inner and lower ends to the outside of the chute, preferably by electric welding.

85 Each hanger flap extends upwardly and somewhat outwardly from its point of connection with the chute over the top edge of a vertical plate 95 12 and thence downwardly to a suitable fastening at 13.

The fastening of the outer end of the hanger is desirably effected by clamping the end down to a fixed horizontal plate 14, as by a nut and bolt 15 and upper plate 16, the bend of nearly 180° at the upper edge of the plate 12 and of approximately 90° at the fastening plate 16 greatly lessening the lateral pull upon the flap at its point of outer fastening. As shown, the bolt 15 will preferably not extend through the floor.

100 The plate 12 is preferably individual to the hanger and desirably comprises an inner and vertical side of a horizontal angle 17, each 110

hanger being then provided with a separate angle.

While obviously I may make the plate 12 common to all the hangers, for example a circular angle plate surrounding the chute, I prefer however to keep the plate supports of the individual hangers individually independent, both because the structure is then better adapted to very easily accommodate individually different conditions at different floors or at the same floor and also because it is less expensive to install.

The angles 17 are preferably straight and of any suitable length and are fastened to the floor structure with one flange 18 horizontal and the other flange 12 directed vertically upward.

I secure the flange to the floor structure in any suitable way as by bolts 19, and then extend the hanger up over the vertical flange and thence downward to the horizontal outwardly extending flange 18, fastening it to place against the flat flange by the bolt 15 and rectangular washer 16, as clearly indicated in the figures.

The number of hangers required at each floor will of course vary with the individual chute. I prefer to use four, as shown in Figures 1 and 2, but I can use two with good results, as indicated in Figure 3. Two hangers are advantageous because the chute will assume the vertical automatically. Where two hangers are to be employed at a floor having a rectangular opening, I will preferably secure the hangers at opposite corners of the opening, as shown.

In view of my invention and disclosure variations and modifications to meet individual whims or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. In a chute of the character indicated, an aluminum chute section passing through a floor opening, a flap of aluminum having one end welded to the outside of the chute, a member carried by the floor and having an upwardly directed edge, said flap extending upwardly from its said one end over the edge and thence downwardly and means fastening the outer end of the flap after it has extended downwardly from the upper edge of the flange.

2. In a chute of the character indicated, floor structure passing the chute, a metal angle supported on the structure and having a vertical

flange near the chute and a horizontal flange extending therefrom outwardly with respect to the chute in combination with a metal flap having a high intermediate portion supported on the upwardly directed edge of the vertical flange and low inner and outer ends fastened respectively to the outside of the chute and to the top of the horizontal flange.

3. In a chute of the character indicated, a floor structure passing the chute, a metal angle supported on the structure and having a vertical flange near the chute and a horizontal flange extending therefrom outwardly with respect to the chute in combination with a metal flap, having a high intermediate portion supported on the upwardly directed edge of the vertical flange and low inner and outer ends respectively welded to the outside of the chute and fastened to the top of the horizontal flange.

4. In a chute of the character indicated, floor structure passing the chute, a metal angle supported on the structure and having a vertical flange near the chute and a horizontal flange extending therefrom outwardly with respect to the chute in combination with a metal flap, having a high intermediate portion supported on the upwardly directed edge of the vertical flange and lower inner and outer ends respectively welded to the outside of the chute and fastened to the top of the horizontal flange with the outer end clamped flat down to the top of the horizontal flange.

5. In a chute of the character indicated, floor structure passing the chute, a plurality of straight metal angles supported on the structure at intervals around the chute and each having a vertical flange near the chute and a horizontal flange extending therefrom outwardly with respect to the chute in combination with a metal flap at each angle having a high intermediate portion supported on the upwardly directed edge of the vertical flange and low inner and outer ends fastened respectively to the outside of the chute and to the top of the horizontal flange.

6. In a chute of the character indicated, a chute section passing through a floor opening, a plurality of angles having vertical and horizontal flanges directed respectively upwardly and outwardly and metal flaps fastened to the outside of the chute at the respective angles and extending up from the point of fastening over the vertical flanges and thence downwardly fastening to the horizontal flanges.
